UNITED STATES PATENT OFFICE.

GEORGE C. FATSCHER, OF LAKEWOOD, OHIO.

SAND-CUTTING APPLIANCE.

1,316,884.

Specification of Letters Patent. Patented Sept. 23, 1919.

Application filed May 2, 1917. Serial No. 165,819.

To all whom it may concern:

Be it known that I, GEORGE C. FATSCHER, a subject of the Emperor of Germany, residing at No. 1568 Warren road, city of

5 Lakewood, in the county of Cuyahoga and State of Ohio, have invented a new and useful Improvement in Sand-Cutting Appliances, of which the following is a specification, the principle of the invention being 10 herein explained and the best mode in which I have contemplated applying that principle, so as to distinguish it from other inventions.

This invention pertains to a sand cutting 15 appliance and the method of its use, both particularly adapted according to the exemplification disclosed by the drawings to molder's sand as employed in foundries.

After the sand has served its purpose of 20 holding the shape of a certain pattern and the casting has been poured it becomes necessary not only to remove the sand from the molder's flask but to reseparate it into its component particles and to remix the same 25 so that it has a more homogeneous character, as for example, its degree of moisture. It is still common practice to dump molder's sand onto a heap and to then mix the same by repeated shovel turnovers. One 30 object of my invention is to cut or loosen the sand into its integral particles while the same is in a molder's flask. Another object is to provide pneumatic conveyance and distribution thereof. A further object is to 35 effect a continuity in the operation of cutting and conveying the same and to make provision for depositing the same upon one or more molding benches.

With the foregoing and other objects in 40 view the invention consists of the novel construction, combination and arrangement of parts as hereinafter more specifically described and illustrated in the accompanying drawings, wherein is shown an embodiment 45 of the invention, but it is to be understood that changes, variations and modifications can be resorted to which come within the scope of the claims hereunto appended.

50 Adverting to the drawings: Figure I is an elevation showing an arrangement of parts embodying my invention, and the manner of putting the same into practice.

Fig. II is mainly an enlarged section of

the principal detail which features my invention, some of the parts being shown in elevation.

Fig. III is an end view of one extremity of Fig. II.

In Fig. I, I have shown a molder's flask 1 and bench 2 separated a suitable distance. Supported above, in any approved manner, is a sand hopper 3 having a converging bottom 4 from which a pipe 5 leads to a valve 6 positioned over the bench 2 such that sand 65 may be supplied to the bench 2 in any quantity when and as desired. The extreme lower end of the hopper is provided with an inlet pipe 7. The top of the hopper is provided with an outlet 8 communicating 70 with a tube 9 leading to a suction fan 10 which is provided with a driving pulley 11. Interiorly the hopper has a partition or baffle 12 extending upwardly a given distance upon the inlet opening 7 and higher 75 up another transom baffle 13 which is so positioned as to be interposed between the inlet 7 and outlet 8.

A pneumatic nozzle 14 is provided with a head 15 in screw threaded connection 80 therewith, such head having an enlarged conical nose 16 fashioned with equispaced apertures 17 such that a spider structure 18 composed of four divaricating extensions is formed. It is understood that the nozzle 85 14 as well as its head 15 are hollow and that the apertures 17 are in open communication therethrough. The nozzle 14 is rotatably mounted in two sets of ball bearings 19 and carries, fixed to itself between 90 such bearings, a turbine rotor 20 movable in an annular chamber 21 with one side of which a flared impulse inlet 22 communicates. Any suitable motive fluid, such as compressed air, may be fed through a hose 95 23 to such inlet 22. Fixed in any feasible manner to one side of the supporting casting of the nozzle 14 is a socket 24 in which a handle 25 is secured. A portion 26 of the nozzle 14 extends beyond the bearings 100 19 and carries a disk 27 movable between ball bearings 28 which are held in place by a clamping structure 29, one part of which carries a nipple 30 so as to be in open communication with the end 26 of 105 the nozzle. A flexible hose 31 connects the inlet 7 with the nipple 30 to which it is shown attached by means of a hose plant 32.

The operation of my invention is as follows:

Assuming the compressed air to have been turned, the velocity of the compressed air lends impulse to the rotor 20 and causes it to be very rapidly revolved and therefore likewise the nose 18 which is to be presented to the collection of sand which it is purposed to remove. Meanwhile the suction 10 effect should have been created in the tube 31 in response to starting of the fan 10. Owing to the formation of the nose as described, the same effectually loosens the sand and causes it to be drawn through the 15 nozzle with a whirling motion whence it is conducted to the hopper 3 and caused violently to impinge against the baffle 13 which precludes its egress through the outlet 8. In consequence it settles gravitationally into the bottom 4. The configuration of the head of the nozzle is designed to more effectually cut the sand and enable it to be withdrawn through the nozzle as will be 20 evident to those familiar with the art.

I claim:

1. A sand cutting appliance comprising a rotary suction nozzle having an inlet opening and a conical spider nose having portions presented obliquely with reference to its axis.
2. A sand cutting appliance comprising a rotary suction nozzle having an enlarged centrally pointed end provided with slots oblique relative to the axis of rotation.
3. A sand cutting appliance comprising a hollow member having one end open, suction means connected with the other end, a rotor

carried by said member, and means for impinging a motive fluid against said rotor.

4. A sand cutting appliance comprising a 40 rotatable nozzle provided with a conical nose having a series of slots therein, whereby a spider structure is formed and means for rotating said nozzle.

5. A sand cutting appliance comprising a 45 hollow rotatable nozzle provided with a solidly pointed end structure of spider formation whereby a series of slot inlets divaricating from its solid center are produced, means for rotating said nozzle, and means 50 for creating a suction effect therethrough.

6. A sand cutting appliance comprising the combination of a receptacle having an inlet and an outlet, suction means operatively connected with said outlet, a portable rotary suction nozzle flexibly connected with said inlet and having an open nose, a baffle interposed between said inlet and outlet, and means for rotating said nozzle.

7. A sand cutting appliance comprising 60 the combination of a hopper having a valve controlled opening adapted to discharge upon a molding bench, said hopper being additionally provided with an inlet and an outlet, a baffling device interposed between 65 said inlet and outlet, suction means connected with said outlet, a hollow rotary sand cutting nozzle flexibly connected with said inlet so as to enable insertion in a flask, and means for rotating said nozzle.

Signed by me this 28th day of April, 1917.

GEORGE C. FATSCHER.
